CLAIM

The ornamental design for a fidget toy gun with bullet assembly, as shown and described.

DESCRIPTION

FIG. 1 is a front, top, right side perspective view of a fidget toy gun with bullet assembly, showing my new design; FIG. 2 is a rear, bottom, left side perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; and, FIG. 8 is a bottom plan view thereof.
The broken lines show the features of the fidget toy gun with bullet assembly that form no part of the claimed design.

1 Claim, 8 Drawing Sheets
